CLAIM

The ornamental design for a vehicle bumper, as shown and described.

DESCRIPTION

FIG. 1 is a front perspective view of a vehicle bumper showing my new design;

FIG. 2 is a front elevation a view thereof;

FIG. 3 is a rear elevational view thereof;

FIG. 4 is a top plan view thereof;

FIG. 5 is a bottom plan view thereof;

FIG. 6 is a side elevational view thereof;

FIG. 7 is an opposite side elevation view thereof;

FIG. 8 is a front elevational view a vehicle bumper showing a second embodiment of my new design, it is to be understood that all other views of the second embodiment are the same as in FIGS. 4-7; and,

FIG. 9 is a rear elevational view of FIG. 8.

The broken line showing of a vehicle in FIG. 1 is for illustrative purposes only and forms no part of the claimed design.
